UNITED STATES PATENT OFFICE

HARLEY E. ANDERSON, OF KANSAS CITY, MISSOURI, ASSIGNOR TO GUSTIN-BACON MANUFACTURING CO., OF KANSAS CITY, MISSOURI, A CORPORATION OF MISSOURI

SLACK ADJUSTER

Application filed June 24, 1930. Serial No. 463,374.

My invention relates to that class of slack adjusters described in my copending application, Serial No. 437,153.

All slack adjusters of this type, with which I am familiar, are subject to the objection that when it becomes necessary to replace the brake shoes with new ones, due to the old ones being worn out, the dogs which engage the rack must be pulled downwardly until they clear the rack, and held there while the rack bar is being pushed back, as the strain was on the rack and dogs.

My invention has for its principal object, to provide a construction which will permit the workman to turn the rack bar a quarter turn, which rotation will retract the dogs by compressing the two springs under the dogs, and the rack bar can be freely drawn back the required distance. I also provide a construction which will make it impossible to reconnect the top rod to the truck lever until the rack bar is returned to its normal position, in which the dogs will be in engagement with the teeth of the rack bar.

A further object is, to construct the device so that the rack will be under compression. In the old type it was under tension, and as a consequence, when the brakes were applied any internal weakness in the rack, such as flaws, etc., would cause the rack to break or pull in two, and thus bring about a failure of the brakes. In my improved construction, such an event cannot occur, as the rack is never subject to tension.

A further object of my invention is, to provide for closer connection to the cylinder lever, thus bringing the top rod more nearly in a horizontal line, which is most desirable in a device of this type.

A further object of my invention is, to shorten the overall length of the rack by reducing the overhang, and extending the top rod through the rack.

A concrete embodiment of my invention is illustrated in the accompanying drawings, to be considered as part of this specification, in which—

Fig. 1 is a phantom top plan view through the floor of a freight car, showing my improved slack adjuster;

Fig. 2 is a side view of the device as shown in Fig. 1, partly in section, showing the position of the device when the brakes are in released position;

Fig. 3 is a detail view, showing the position of the device when the brakes are set, with no wear on the brake shoes;

Fig. 4 is a similar view, showing the position of the device with the brakes set, where the brake shoes on the wheels have partially worn off and the device has taken up the slack;

Fig. 5 is a view similar to Fig. 4, showing the device being compensated for the wear on the brake shoes;

Fig. 6 is an enlarged fragmentary top plan view;

Fig. 7 is the same in side elevation;

Fig. 8 is a side view of the device as shown in Fig. 6, with the slack adjuster shown in section; and

Fig. 9 is a sectional view, taken on line 9—9 in Fig. 8.

Similar reference numerals refer to similar parts throughout the entire description.

As shown in the drawings, the brake cylinder 1 is connected to links 2, which in turn are connected to the cylinder levers 3 and 4. As the construction is duplicated for each end of the car, I shall confine my description to the device in connection with only one end of the car.

The vertical truck lever 5 is connected to the brake jaw 6 on the end of the top rod 7, by means of the brake pin 8. The other end of the top rod 7 is provided with threads 9, which fit internal threads cut in the rack casting 10. This rack casting 10, as clearly seen in the cross-section Fig. 9, is round, and has a plurality of teeth 11 formed on a portion of its periphery. An opening 12 extends longitudinally of the rack casting 10. The top rod 7 extends through this opening 12, and is screwed into threads in the rack casting 10. A nut 13 is then screwed tightly on to the top rod 7, and its end 14 is peened or riveted over, thus effectually preventing the loosening of the nut 13.

A rib 15, which serves as a detent, is cast or formed on the exterior surface of the rack

casting 10, and extends for the full length thereof. The rack casting 10 is slidably mounted in a housing 16, which has a downwardly extending portion 17, in which is formed a vertical cylindrical recess 18, in which I mount a dog 19, one end 20 of which engages teeth 11 of the rack 10. A coil spring 21 serves to hold the dog 19 normally projected from the cylindrical recess 18 in which it is mounted, and in engagement with the rack teeth 11.

A chamber 22 is formed in the portion 17, in which I mount a coil spring 23, which extends into an extension 24, formed on what I term a cross head 25. This cross head 25 also has a vertical cylindrical recess 26, in which I mount a dog 27, which corresponds in all respects to the dog 19, a coil spring 28 serving to hold it in engagement with the teeth 11 of the rack casting 10.

To prevent the rack casting 10 sliding out of the housing 16, I form a stop or collar 36 on the end of the rack casting 10, which may be cast integral therewith, or secured in position by a set screw, or by any other convenient form for fastening a stop collar.

The housing 16 has an upper portion 29, into which the end of the cylinder lever 3 extends, and which is pivotally secured to the housing 16 by means of a special brake pin 30, which is formed without a head, thus bringing the cylinder lever 3 closer to the top rod 7 than would otherwise be possible. The pin 30 is prevented from working out, by means of a cotter pin 31, mounted in the wall of the housing 16.

A permanent stop 32 is suitably secured to the car, for the cross head 25 to abut in the manner hereinafter set forth. The housing 16 has as an arcuate slot 33 formed in one of its side walls, in which is located the rib 15, which abuts the shoulders 34 and 35 at the ends of said slot 33. A similar slot is formed in the wall of the cross head 25.

The operation of the device is as follows: The air being admitted into the cylinder 1, its piston shifts the links 2 and in turn the cylinder lever 3. This moves the top rod 7, and consequently the vertical truck live lever 5, and the brakes are applied. My device is set so that with a movement of the air piston of not less than seven nor more than nine inches, as is required, the cross head 25 will abut the permanent stop 32. If the brake shoes wear, the top rod 7 will attempt to carry the housing 16 farther; this being prevented by the stop 32, the spring 20 will be compressed, and the dog 27 will be advanced a distance sufficient to take up the slack. As the brakes are released, the spring 20 will expand and advance the housing 16, until the dog 19 engages the correct tooth 11 on the rack 10. The collar 36, abutting the housing 16, prevents the rack casting 10, from sliding out of the housing 16. In this manner, the device

automatically takes up the slack, maintaining at all times the same amount of air piston travel, thus holding the cylinder levers 3 and 4 at approximate right angles to the center line of the air cylinder 1, which is the ideal operating condition.

When the brake shoes are worn out, and it becomes necessary to apply new shoes, the car repairer first pulls the pin 8, which connects the top rod 7 to the vertical truck line lever 5; he can then apply the new shoes, as the beams can be easily moved away from the wheels, because the truck lever 5 is disconnected from the top rod 7. But when the workman attempts to reconnect top rod 7, it is impossible, because it is now too short to meet the lever 5—since it has been automatically shortened by my device taking up the slack produced by the wearing of the shoes. He then turns the top rod 7 by hand, which carries with it the rack 10, being secured thereto by the threads 9 and the nut 13. This rotation compresses the dogs 19 and 27, and the rod 7 and rack 10 are free to slide on the housing 16 until the rod 7 is long enough to connect to the lever 5. By the stop collar 36, the rack 10 is prevented from either being pulled entirely out of the housing 16, or to a point where the end of rack 10 would be inside the cross head 25 and the dogs 19 and 27 could not mesh with the teeth 11 of the rack 10; this could not be seen or noted until attention was drawn thereto by failure of the device to function. The connection between rod 7 and lever 5 can not be made, because the workman has rotated the rod 7 a quarter of a revolution and the jaws 6 no longer register with the lever 5, so he must turn the rod 7 back in order to insert the pin 8. By so doing, the rack 10 is automatically reset so that the dogs 19 and 27 will again engage the teeth 11 of the rack 10, and the device is again ready for operation.

The rib or detent 15 and the shoulders 34 and 35 are provided, so the workman can not continue to rotate the top rod 7 until the teeth 11 of rack 10 are on top and the dogs 18 and 27 underneath, as the device would then be inoperative. But with the rib 15 and shoulders 34 and 35 constructed as described, he must turn the rod 7 back to the position in which it was when he disconnected it, which resets the rack 10 in the proper operative position. In fact, unless he does this, he can not possibly connect the rod 7 to the lever 5; and the provision of the collar 36 permits necessary adjustment of the device without risk of pulling the rack 10 entirely out of the housing 16. By locating the cylinder lever 3 at the top of the housing 16, it is apparent I shorten the over-all length of the device and gain considerable more take-up, without any increase of the overhang of the rack 10.

Having described my invention, what I re-

gard as new, and desire to secure by Letters Patent of the United States, is:

1. In an automatic slack adjuster, a round sleeve, teeth cut on the outside thereof, dogs which engage said teeth, said sleeve being capable of rotation for a predetermined distance, and means to prevent its rotation beyond said point.

2. In an automatic slack adjuster, a round sleeve, teeth cut on the outside thereof, spring-pressed dogs which engage said teeth, said sleeve being capable of rotation for a predetermined distance, and means to prevent its rotation beyond said point.

3. In an automatic slack adjuster, a round sleeve, teeth cut on the outside thereof, a housing in which said sleeve slides, said housing having downwardly depending and upwardly extending portions, a cross head, an extension thereon which slides into a chamber in said downwardly depending portion, a spring which holds said extension normally projected therefrom, a dog mounted in said housing, a spring to hold said dog in engagement with the teeth on said sleeve, a similar dog and spring in said cross head, said sleeve being secured to the top rod of an air brake rigging, a longitudinal rib on said sleeve located in an arcuate slot in said housing, the ends of which limit the rotation of said sleeve, means to connect the upwardly extending portion of the housing to the cylinder lever of an air brake, and a permanent stop which said cross head abuts.

4. The combination, with an air brake rigging, of a round sleeve, through which the top rod of the brake rigging extends, threads on said rod which fit threads in said sleeve, a nut to secure said rod and said sleeve together, teeth cut on the outside of said sleeve, a housing in which said sleeve slides, a dog in said housing which engages said teeth, a cross head slidably connected to said housing, a dog in said cross head which engages said teeth, said sleeve being capable of rotation for a predetermined distance, and means to prevent such rotation beyond said point.

5. An automatic slack adjuster, connected to the top rod of an air brake rigging, comprising a housing, a cross head, a rack, dogs which engage said rack, springs which hold said dogs normally in said engagement, in arrangement so that the rotation of said rack will compress said springs and disengage said dogs, and means to limit the amount of such rotation.

6. An automatic slack adjuster, connected to the top rod of an air brake rigging, comprising a housing, a cross head, a rack, dogs which engage said rack, springs which hold said dogs normally in said engagement, in arrangement so that the rotation of said rack will compress said springs and disengage said dogs, means to limit the amount of said rotation, means to connect the cylinder lever to

the top of said housing, and means to prevent said last named means being disconnected.

7. An automatic slack adjuster, connected to the top rod of an air brake rigging, comprising a housing, a cross head, a rack, dogs which engage said rack, springs which hold said dogs normally in said engagement, in arrangement so that the rotation of said rack will compress said springs and disengage said dogs, means to limit the amount of said rotation, a pin which connects the cylinder lever to the top of said housing, and means to hold said pin in place.

8. An automatic slack adjuster, connected to the top rod of an air brake rigging, comprising a housing, a cross head slidably engaged therewith, a spring to hold said cross head normally projected from said housing, a rack fixedly secured to said top rod, dogs which engage said rack, springs which hold said dogs normally in said engagement, in arrangement so that the rotation of said rack will compress said springs and disengage said dogs, means to limit the amount of said rotation, and a stop on said rack which abuts said cross head.

9. The combination, with an air brake rigging, of a round sleeve, through which the top rod of the air brake rigging extends, means to fixedly secure said rod to said sleeve, teeth cut on the outside of said sleeve, a housing in which said sleeve slides, a dog in said housing which engages said teeth, a cross head slidably connected to said housing, a dog in said cross head which engages said teeth, said sleeve being capable of rotation a distance sufficient to disengage said dogs from said teeth, and means to prevent such rotation beyond said point.

10. The combination, with an air brake rigging, of a round sleeve, through which the top rod of the brake rigging extends, threads on said rod which fit threads in said sleeve, a nut to secure said rod and said sleeve together, teeth cut on the outside of said sleeve, a housing in which said sleeve slides, a dog in said housing which engages said teeth, a cross head slidably connected to said housing, a spring to hold said cross head normally projected from said housing, a dog in said cross head which engages said teeth, said sleeve being capable of rotation a distance sufficient to disengage said dogs from said teeth, and means to prevent such rotation beyond said point.

11. The combination, with an air brake rigging, of a round sleeve, through which the top rod of the brake rigging extends, means to fixedly secure said rod to said sleeve, teeth cut on the outside of said sleeve, a housing in which said sleeve slides, a dog in said housing which engages said teeth, a cross head slidably connected to said housing, a spring to hold said cross head normally projected from said housing, a dog in said cross head

which engages said teeth, said sleeve being capable of rotation a distance sufficient to disengage said dogs from said teeth, and means to prevent such rotation beyond said point.

5 12. An automatic slack adjuster, connected to the top rod of an air brake rigging, comprising a housing, a cross head, a rack, dogs which engage said rack, in arrangement so that the rotation of said rack will disengage 10 said dogs, and means to limit the amount of said rotation.

12. An automatic slack adjuster connected to the top rod of an air brake rigging, comprising a housing, a cross-head, a rack, dogs 15 which engage said rack, springs which hold said dogs normally in engagement in arrangement so that the rotation of said rack will compress said springs and disengage said dogs, means to limit the amount of such rotation and means to prevent the longitudinal 20 movement of the rack in said housing beyond the predetermined point.

14. An automatic slack adjuster, connected to the top rod of an air brake rigging, comprising a housing, a cross head, a rack, dogs which engage said rack, in arrangement so that the rotation of said rack will disengage 25 said dogs, means to limit the amount of said rotation and means to prevent the longitudinal 30 movement of the rack in said housing beyond the predetermined point.
